UNITED STATES PATENT OFFICE.

UMBERTO MAGNI, OF LOS ANGELES, CALIFORNIA.

RADIATOR.

1,401,343.

Specification of Letters Patent. Patented Dec. 27, 1921.

Application filed November 2, 1920. Serial No. 421,302.

To all whom it may concern:

Be it known that I, UMBERTO MAGNI, a citizen of the United States, residing at Los Angeles, in the county of Los Angeles and State of California, have invented certain new and useful Improvements in Radiators, of which the following is a specification.

This invention relates to certain new and useful improvements in radiators especially adapted for use in the cooling system of internal combustion engines and it primarily has for one of its objects to provide an enlarged water capacity with a greater heat radiating surface within a given area than has heretofore been provided.

Another object of the invention is to provide a radiator of staunch construction which will withstand the shocks and vibrations of usage without springing a leak and to that end I provide a set of units separated by a partition plate which is so designed and constructed that it will serve to interlock the adjacent units with the solder that holds the parts together the plate itself serving the additional function of providing more radiation surface.

A further object is to provide a partition and strengthening plate which embodies a relatively small amount of metal, thereby reducing the cost of manufacture, and to that end and for the additional purpose of stirring up the air currents passing through the cells, I perforate the plate at frequent intervals where it will not affect the strengthening function of the plate or its function as a means for interlocking with the water tube units.

Another object of the invention is to provide a radiator which will accomplish the above purposes and yet will not differ in appearance from other cellular radiators of the square hole type.

In the accompanying drawings—

Figure 1 is a front elevation of a portion of an automobile radiator embodying my invention.

Fig. 2 is an enlarged detail perspective view of a part of two sections of water tube units embodying my invention.

Fig. 3 is a detail vertical section on the line 3-3 of Fig. 5.

Fig. 4 is a detail side elevation of a portion of one water tube unit.

Fig. 5 is a horizontal section on the line 5-5 of Fig. 3.

Fig. 6 is a detail perspective view of a portion of one partition plate.

Fig. 7 is a view similar to Fig. 6 showing a modified form of partition plate, i. e. one having differently formed openings.

In the drawings in which like letters and numbers of reference indicate like parts in all the figures, 1 is a strip of suitable metal from which one-half of a water tube is made. The strip 1 is bent upon itself laterally at suitable intervals as at 6 the edges of the strip being brought together and soldered as at 5.

The vertical part of the strip 1 is caved as at 2 so that the edges of adjacent half-units may be brought together and soldered as at 7 thus leaving vertical water passages 20 with lateral pockets 60 to form a reservoir for the water which is to circulate through the same. A water tube unit consists of two strips 1 shaped as shown and above described.

In order to firmly fasten the adjacent units of the radiator together as well as to offer additional metal to radiate the heat and conduct it from the circulating water I provide a partition plate 8 between each pair of water tube units. This plate constitutes one of the essential features of the present invention. It consists of a thin sheet of metal having, at suitable intervals, transverse ridges 9 and grooves 10, the latter being located between the former, the ridges 9, also providing grooves 11 for a purpose later explained. The plate 8 is provided with holes or passages 12 through the same, the exact shape or form of the holes being immaterial so long as they do not interfere with the function of the plate as an interlocking and strengthening medium for the adjacent water-tube units. From the drawings it will also be observed that the grooves 10 alternate to opposite sides of the plate 8 and are the same distance apart as are the bends of the laterals 6 so as to receive the same and when solder is placed in the grooves 11 to secure the plate and water tube units together, a tendency of the units to slide up and down on the plate is avoided.

It will also be seen that while solder may be used to secure the units to the plate in the grooves 10 as well as in the grooves 11 yet by reason of the fact that the bends of the laterals 6 of the units rest, throughout

their lengths in the grooves 10 it will only be necessary to solder alternate ones where the solder 13 will engage in the grooves 11 and with the adjacent bend of the lateral 6.

5 This reduces the amount of solder usually used in radiators of similar size heretofore in common use and thereby further lowers the expense of construction.

The top and bottom of the strips 1 are 10 folded over singly as at 2 and soldered fast to the plate 8.

From the foregoing it will be seen that by my design of radiator the water capacity is relatively large and the radiating surface of 15 metal is increased without interfering with the free air passage and without adding materially to the expense of manufacture. From the foregoing description taken in connection with the accompanying drawings it is thought that the complete construc- 20

tion and advantages of the invention will be clear to those skilled in the art to which it appertains.

What I claim is:

In a radiator having water-tube units 25 provided with lateral projecting portions; a partition plate having transverse grooves to receive alternate ones of said projections of a unit on one side of the plate and having transverse grooves to receive other 30 alternate ones of said projections of a unit on the other side of the plate, and means securing the plate to the respective units, said last named means comprising soldering grooves in the partition plate at and on the 35 opposite side of the plate to the grooves which receive the lateral projections of the water-tube units, and solder in said soldering grooves.

UMBERTO MAGNI.
